UNITED STATES PATENT OFFICE.

WILLIAM H. SAUVAGE, OF NEW YORK, N. Y., ASSIGNOR, BY MESNE ASSIGNMENTS, TO
GOULD COUPLER COMPANY, OF NEW YORK, N. Y.

SLACK ADJUSTER.

Application filed November 25, 1921. Serial No. 517,629.

To all whom it may concern:

Be it known that I, WILLIAM H. SAUVAGE, citizen of the United States, residing at New York, in the county of New York and 5 State of New York, have invented certain new and useful Improvements in Slack Adjusters, of which the following is a specification.

This invention relates to improvements in 10 slack adjusters and more particularly to automatic slack adjusters adapted to be used with the brake rigging of railway vehicles of all kinds. While the construction will be hereinafter described with relation to its 15 several forms as applied to the truck brake rigging of passengers, freight cars, locomotive tenders and pony trucks, it is, of course, to be understood that without material modification the invention is applicable to 20 the truck brake rigging of other cars, as well as to the foundation brake rigging beneath the car body and between the end trucks.

One of the objects of the present invention 25 is to provide a simple and practical slack adjuster, particularly adapted for use in connection with a truck brake rigging of positive and durable construction, as well as one which will at all times be reliable and 30 efficient in use and operation.

A further object is to provide a practical slack adjuster adapted to insure uniform brake shoe clearance and uniform and positive travel or movement of the source of 35 power used in applying the brakes.

A further object is to provide an improved slack adjuster which may be easily, quickly, and positively manipulated and adjusted for replacing worn brake shoes and 40 one which will automatically assume properly adjusted position on the first application of the brakes after replacement of parts.

Other objects will be in part obvious and in part hereinafter pointed out in connection 45 with the accompanying sheets of drawings showing several of the various possible modifications and applications of the invention to truck brake rigging of various types.

In these drawings, wherein similar reference characters indicate corresponding parts,—

Figure 1 is a plan view showing such parts of the slack adjuster and associated 50 brake rigging as are necessary to understand 55 the invention;

Figure 2 is an end elevational view of certain parts shown in Figure 1;

Figure 3 is an elevational view showing the modified form of slack adjuster as applied to the lower ends of the live and dead 60 levers of a four-wheel truck;

Figure 4 is a similar view showing the levers inclined oppositely at an angle of 40° as those shown in Figure 3, thereby disclosing the slack adjuster in a correspondingly 65 turned position;

Figures 5 and 6 are views similar to Figures 3 and 4, respectively, showing a slack adjuster of similar type connecting the central parts of the live and dead levers; 70

Figure 7 is an end view of the part shown in Figure 4; and

Figure 8 is a detail sectional view of the take up and holding housings.

Referring now to the drawings in detail 75 and more particularly to Figure 1, there is indicated at 10 two brake beams of an ordinary four-wheeled truck which are adapted to move apart or away from each other on application of the brakes. These brake beams are each provided near their central parts with struts 11 in which are pivoted at 12 a dead lever 13 and a live lever 14. The dead lever can be secured at 15 to any relatively fixed part of the truck or rear cylinder lever, as desired, while power is applied to the point 16 moving in the direction of the arrow, to apply the brakes, the levers being supported in suitable guides 17, one of which is provided with a stop 18 for the 90 dead lever.

Connecting the central parts of the live and dead lever is a two-part telescopic push rod, the barrel part 20 being pivoted at 21 to the live lever, while the rod part 22 is 95 pivoted at 23 to the dead lever. The tubular part 20 is provided with a housing 24 containing a plurality of holding means, such as the customary holding dogs 25 which 100 contact with the rod member 22 to prevent a normal inward movement thereof on application of the brakes. These dogs are held in canted or biting position, by means of a coiled spring 26 acting between an end wall 27 of the housing and the adjacent dog 25. Loosely mounted upon the rod 22 is a 105 second housing 28 containing preferably a single dog 30, although others may be employed if desired, which dog is normally held in canted position by means of a coiled 110

spring 31 acting between the adjacent face of the dog and the inner left hand face of the housing. The housing is provided with a plurality of trunnions 32, as better shown, perhaps, in Figure 2, to which is pivotally connected a duplex clevis 33 terminating in a nut 34 in which is screwed a bolt 35 provided with a head 36, freely movable in a stirrup or U-shaped member 37, pivotally connected to the live lever, preferably at the point 38, although this is not essential for, if desired, it could be pivoted to the point 12 as well. It will be noted that the dog 30 and the end dog 25' are elongated and provided with a hole through which a releasing rod 40 is adapted to pass. This releasing rod has a stop lug or bent portion 41 adapted to engage the dog 30 and upwardly turned end stop 42 adapted to coact with the dog 25. A handle or eye 43 at the opposite end is provided for manipulation. It will, of course, appear obvious that when this releasing rod 40 has moved towards the left the lugs 41 and 42 will coact respectively with the dogs 30 and 25 and move the same to a position at right angles to the rod 22 against the action of the springs 31 and 26, and, when in this position, the rod 22 is free to move in either direction with respect to the tubular portion 20.

Attention is directed particularly to the space between the head of the bolt 36 and the bottom of the stirrup 37 with which it is adapted to coact and indicated by the line 44. This space provides for a certain lost motion to insure brake shoe clearance and this lost motion must be taken up before the slack adjuster comes into compression. It will also be noted that the two housings 28 and 24 are connected by interfitting lugs 45 and 46 provided with a slotted connection, as indicated by the slot 47 and bolt 48. This connection permits certain relative movement between the two housings towards and from each other, yet insures their alignment at all times. From the above, it will be seen that this construction eliminates the slotted eye heretofore required or deemed necessary in the adjusting rod and, consequently, the necessity of forcing the levers into total or full release position after the slack has been automatically taken up. The weight of the brake beams and slack adjusters will act through gravity and the angularity of the usual brake rigging hangers to move the brake rigging into full released position after any false or excess travel has occurred and is automatically compensated for after each application and release of the braking power. This is a very decided improvement over any and all slack adjusters heretofore indicated and particularly that type wherein the eye of the adjusting rod is so attached to the brake rigging that it has some move-

went which will compress the holding spring 50 interposed between the two housings when any excess movement occurs on application of the brakes. Such full release operation does not occur automatically in that type of slack adjusters where the adjusting rod is secured to a neutral point. In the present construction, no matter how little the excess movement of the live lever may be the slack will be automatically taken up at each and every brake application on release of the same through the action of the adjusting rod compression spring which acts automatically and might be compared to the placing of a non-automatic turn buckle between the live and dead levers.

In operation, power is applied to the live lever 14 to move the same in the direction of the arrow. The bolt 18 adjacent the dead lever acts as a stop for the dead lever for moving relatively to the right since, were it not for this stop, both levers would act as live levers. When equal power is applied, it is immaterial so far as distribution of power goes whether only one or both levers move. In actual practice, however, without the bolt 18 only one or the other of the levers moves to force the brake beams apart and against the wheels. When the live lever moves toward the left, power is transmitted to the barrel moving the same to the left, thence through the dogs to the rod 22, and forces the dead lever and brake beams to the left. The lost motion or brake shoe clearance adjustment obtained between the nut 36 and surface 44 is taken up and if any excess travel occurs the duplex lever 33, acting upon the trunnions 32 of the housing 28, will cause this housing to move relatively toward the right, compressing the take up spring 50. When the live lever moves toward the right on release of the brakes, the parts tend to drop back by gravity or return the springs usually employed to the position shown in Figure 1, and the spring 50 expands to force the housing 28 towards the left. The dog 30, however, having a gripping action upon this rod, will move the same outwardly from the barrel 22, thus automatically taking up the slack an amount exactly equal to the excess travel of the brake rigging.

When it is desired to replace the brake shoes, the tripping mechanism 43 is, or can be, actuated to move the dogs to a position normal to the rod 22, whereupon the rod 22 may be shoved into the barrel and new shoes applied.

In Figures 3 and 4, substantially the same mechanism is shown as applied directly to the live and dead levers of the usual four-wheeled freight truck. The lost motion is provided for by means of an adjustable nut 51 at the end of an adjusting rod 52, pivotally connected at 53 to the fulcrum of

the live lever. This nut is adapted to coact with a lug 54 projecting from the housing 28, which is substantially the same, as is also the housing 24, as the housings previously described in connection with Figure 1, these housings being connected by the slotted construction 47 previously described. The mechanism shown in Figures 5 and 6 is also substantially the same as that above described. Here the push rod 20-22 operates between the central parts, the live and dead levers 13 and 14, adjusting rod 52 being substantially as that shown in Figure 3, and provided with a nut 51 for the lost motion connection with the lug 54 extending from the housing 28.

In Figure 8, there is shown a detailed sectional view of a slightly different form of release mechanism. Obviously this release mechanism can be made in a number of different ways, as, for instance, by putting ears 60 or guide lugs 61 in the pick up box 28 and barrel housing 24, and in extending the dogs as shown instead of as in Figure 1. Thus, by giving the rod 62 a quarter turn lugs 63 and 64 will enter behind the dogs in the pick up box and with a slight pull towards the left unlock the same. Normally the lugs 63 and 64 stand out of the path of travel of the dogs.

It will be seen from the above that all of these several types of slack adjusters work in substantially the same way and its application has wide flexibility in construction, application and uses. The invention is exceedingly simple in practical form and may easily and quickly be applied to the brake rigging now in general use without material alteration or substitution of parts other than the elimination of the solid connecting rod now customarily used between the live and dead levers. The parts are all of durable construction and may be inexpensively manufactured and assembled. In short, the invention is believed to fully accomplish among others all of the objects and advantages herein set forth.

I claim:

1. In a slack adjuster, in combination, a live and a dead lever, a telescopic push rod connecting said levers, a permanent take up and holding means associating with said parts, a temporary take up and holding means associated with one of said parts, and an adjusting rod formed of two parts having a lost motion connection between said parts connecting said latter means with said live lever.

2. In a slack adjuster, in combination, a live and a dead lever, a telescopic push rod connecting said levers, a permanent take up and holding means associated with said parts, a temporary take up and holding means associated with one of said parts, and an adjusting rod comprising a plurality of

parts trunnioned to said last mentioned means at one end and having a lost motion connection between said parts and connected at its opposite end with said live lever.

3. In a slack adjuster, in combination, a live and a dead lever, a telescopic push rod connecting said levers, a permanent take up and holding means associated with said parts, a temporary take up and holding means associated with one of said parts, an adjusting rod comprising a plurality of parts having a lost motion connection between said parts interposed between said latter means and one of said levers, said take up and holding means each comprising a housing, a plurality of holding dogs, and a compression spring acting between said housings.

4. In a slack adjuster, in combination, a live and a dead lever, a telescopic push rod connecting said levers, a permanent take up and holding means associated with said parts, a temporary take up and holding means associated with one of said parts, an adjusting rod interposed between said latter means and one of said levers, said take up and holding means each comprising a housing, a plurality of holding dogs, and a compression spring acting between said housings, said housings having a lost motion connection whereby one may be moved relatively to the other in the direction of the axis of the push rod.

5. In a slack adjuster, in combination, a live and a dead lever, a two part telescopic push rod connecting said parts, a housing formed on the tubular part of the push rod, a plurality of holding devices within said housing, a second housing mounted on the barrel part of said push rod, said housings having a connection therebetween permitting relative longitudinal movement therebetween, a holding means within said housing, and means whereby said second housing is moved along the barrel portion of said push rod on excess travel, and changes the effective length of said push rod after excess travel on release of the brakes and resilient means positioned between said housings adapted to restore the same to normal position after excess travel of the brakes.

6. In a slack adjuster, in combination, a live and a dead lever, a two part telescopic push rod connecting said parts, a housing formed on the tubular part of the push rod, a plurality of holding devices within said housing, a second housing mounted on the barrel part of said push rod, a holding means within said housing, means whereby said second housing is moved along the barrel portion of said push rod on excess travel, and changes the effective length of said push rod after excess travel on release of the brakes, and an adjusting rod comprising a plurality of parts having a lost motion connection be-

- tween said parts connecting said last mentioned housing and the live lever for moving said housing on excess travel.
7. In a slack adjuster, in combination, a live and a dead lever, a two part telescopic push rod connecting said parts, a housing formed on the tubular part of the push rod, a plurality of holding devices within said housing, a second housing having an extensible connection with said first housing and mounted on the barrel part of said push rod, a holding means within said housing, means whereby said second housing is moved along the barrel portion of said push rod on excess travel and changes the effective length of said push rod after excess travel on release of the brakes, and a spring acting between said housings and normally maintaining them a predetermined distance apart.
- 10 8. In a slack adjuster, in combination, live and dead levers, a two part telescopic push rod connecting said parts, a housing formed on the tubular part of the push rod, a plurality of holding devices within said housing, a second housing mounted on the barrel part of said push rod, a holding means within said housing, means whereby said second housing is moved along the barrel portion of said push rod on excess travel and changes the effective length of said push rod after excess travel on release of the brakes, a spring acting between said housings and normally maintaining them a predetermined distance apart, and means connecting said housings adapted to keep them in alignment but permitting relative longitudinal movement.
- 15 9. In a slack adjuster, in combination, a live and a dead lever, a two part telescopic push rod connecting said parts, a housing formed on the tubular part of the push rod, a plurality of holding devices within said housing, a second housing mounted on the barrel part of said push rod, a holding means within said housing, means whereby said second housing is moved along the barrel portion of said push rod on excess travel and changes the effective length of said push rod after excess travel on release of the brakes, a spring acting between said housings and normally maintaining them a predetermined distance apart, means connecting said housings adapted to keep them in alignment, but permitting relative longitudinal movement, and a single means adapted to release the holding means within said housings.
- 20 10. In a slack adjuster, in combination, a live and a dead lever, a telescopic push rod connecting said levers, a housing formed with the outer part of said telescopic push rod, a holding dog within said housing, means normally holding said dogs in biting relation with respect to the other part of said push rod, a second housing on the inner part of said push rod, a holding dog therein, spring means acting between said housings adapted to aid in restoring the parts to normal position on excess travel and after the brakes are released, a second housing having an extensible connection with said first housing and on the inner part of said push rod, a holding dog therein, and spring means acting between said housings adapted to aid in restoring the parts to normal position on excess travel and after the brakes are released.
- 25 11. In a slack adjuster, in combination, a live and a dead lever, a telescopic push rod connecting said levers, a housing formed with the outer part of said telescopic push rod, a holding dog within said housing, means normally holding said dogs in biting relation with respect to the other part of said push rod, a second housing on the inner part of said push rod, a holding dog therein, spring means acting between said housings adapted to aid in restoring the parts to normal position on excess travel and after the brakes are released, and a single means adapted to move both of said holding dogs to a position at right angles to the inner part of said push rod, whereby said inner part may move freely in either direction.
- 30 12. In a slack adjuster, in combination, a live and a dead lever, a telescopic push rod connecting said levers, a housing formed with the outer part of said telescopic push rod, a holding dog within said housing, means normally holding said dogs in biting relation with respect to the other part of said push rod, a second housing on the inner part of said push rod, a holding dog therein, spring means acting between said housings adapted to aid in restoring the parts to normal position on excess travel and after the brakes are released, and a single means adapted to move both of said holding dogs to a position at right angles to the inner part of said push rod, whereby the said inner part may move freely in either direction, and an adjusting rod connecting said housing on the inner part of said push rod with the live lever.
- 35 13. In a slack adjuster, in combination, a live and a dead lever, a telescopic push rod connecting said levers, a housing formed within the outer part of said telescopic push rod, a holding dog within said housing, means normally holding said dogs in biting relation with respect to the other part of said push rod, a second housing on the inner part of said push rod, a holding dog therein, spring means acting between said housings adapted to aid in restoring the parts to normal position on excess travel and after the brakes are released, a single means adapted to move both of said holding dogs to a position at right angles to the inner part of said push rod, whereby the said inner part may move freely in either direction, an adjusting rod connecting said housing on the inner part of said push rod with the live lever, said push

rod being formed in two parts having a lost motion connection thereby to insure brake shoe clearance.

14. In a slack adjuster, in combination, a live lever, a dead lever, a two-part telescopic push rod, a housing formed on the outer part of said push rod, a second housing mounted on the inner part of said push rod, holding means in both housings and a single means for releasing both of said holding means.

15. In a slack adjuster, in combination, a live lever, a dead lever, a two part telescopic push rod, a housing formed on the outer part of said push rod, a second housing mounted on the inner part of said push rod, holding means in both housings, a single means for releasing both of said holding means, a compression spring acting between 20 said housings adapted to move said housing on the inner part of said push rod to normal position when the brakes are released if excess travel is taking place, and an adjustable adjusting rod interposed between 25 one of said levers and said housing on the inner part of said push rod.

16. In a slack adjuster, in combination, a live lever, a dead lever, a two part telescopic push rod, a housing formed on the outer 30 part of said push rod, a second housing mounted on the inner part of said push rod, holding means in both housings, a single means for releasing both of said holding means, a compression spring acting between 35 said housings adapted to move said housing on the inner part of said push rod to normal position when the brakes are released if excess travel is taking place, and an adjustable adjusting rod interposed between 40 one of said levers and said housing on the inner part of said push rod, said adjusting rod being formed in two parts with a lost motion connection therebetween adapted to insure brake shoe clearance.

45. 17. In a slack adjuster, in combination, brake beams, struts mounted thereon, live and dead levers carried by said struts, a push rod connecting said levers, and means for limiting the movement of one of said levers.

50 18. In a slack adjuster, in combination, brake beams, struts mounted thereon, guides mounted on said brake-beams, live and dead levers carried by said struts, a push rod connecting said levers, and means comprising a bolt on one of the guides for limiting the movement of the dead lever.

55 19. In a slack adjuster, in combination,

brake beams, struts mounted thereon, guides mounted on said brake-beams, live and dead 60 levers carried by said struts, a push rod connecting said levers, means comprising a bolt on one of the guides for limiting the movement of the dead lever, and a slack adjuster mechanism interposed between the live and 65 dead levers.

20. In a slack adjuster, in combination, brake beams, struts mounted thereon, live and dead levers carried by said struts, a 70 push rod connecting said levers, means comprising a bolt on one of the struts for limiting the movement of the dead lever, and a slack adjuster mechanism interposed between the live and dead levers, said slack 75 adjuster means comprising a two part telescopic push rod, and an adjusting rod interposed between one of said levers and one of the parts of said push rod.

21. In a slack adjuster, in combination, brake beams, struts mounted thereon, live 80 and dead levers carried by said struts, a push rod connecting said levers, means comprising a bolt on one of the struts for limiting the movement of the dead lever, a slack adjuster mechanism interposed between the live and dead levers, said slack adjuster 85 means comprising a two-part telescopic push rod, and an adjusting rod interposed between one of said levers and one of the parts of said push rod, said holding means comprising permanent take up and holding means acting between the inner and outer part of said push rod and temporary take up and holding means directly acting upon the inner part of said push rod.

22. In a slack adjuster, in combination, brake beams, struts mounted thereon, live and dead levers carried by said struts, a push rod connecting said levers, means comprising a bolt on one of the struts for limiting the movement of the dead lever, a slack adjuster mechanism interposed between the live and dead levers, said slack adjuster means comprising a two part telescopic push rod, an adjusting rod interposed 100 between one of said levers and one of the parts of said push rod, said holding means comprising permanent take up and holding means acting between the inner and outer parts of said push rod and temporary take up and holding means directly acting upon the inner part of said push rod, and means for releasing said holding means when it is desired to replace worn brake shoes.

In testimony whereof I affix my signature.

WILLIAM H. SAUVAGE.
